Howard H. Brown

UNITED STATES PATENT OFFICE.

ROBERT W. SCOTT, OF PHILADELPHIA, PENNSYLVANIA, ASSIGNOR OF ONE-HALF TO LOUIS N. D. WILLIAMS, OF ASHBOURNE, PENNSYLVANIA.

GUN-CARTRIDGE.

SPECIFICATION forming part of Letters Patent No. 694,675, dated March 4, 1902.

Application filed October 24, 1901. Serial No. 79,820. (No model.)

To all whom it may concern:

Be it known that I, ROBERT W. SCOTT, a citizen of the United States, residing in Philadelphia, Pennsylvania, have invented certain improvements in Gun-Cartridges, of which the following is a specification.

This invention consists of means for checking or preventing the escape of gas beyond a projectile before it is securely seated in the rifling of a gun. Heretofore bullets used in small-arm ammunition and made of lead could generally be relied upon to upset or expand diametrically upon the shock of discharge, so that but slight escape of gas occurred before the soft metal was well entered in the rifling of the barrel and the gas-vent thereby sealed. The escape of gas around the bullet, even if comparatively slight, is sufficient to materially interfere with the line of flight of the bullet, for if a greater quantity of gas passes at one point on the circumference of the bullet than at another the latter will be eroded or cut away, so as to impair its symmetry and prevent it from following a true flight.

This fact is so well known to expert marksmen that they seldom rely on "fixed ammunition"—that is to say, cartridges having the bullet crimped in the mouth of the cartridge-case—but seat the bullet carefully but firmly in the rifling before introducing the cartridge-case, which contains the explosive only. Even when this method is employed it is questionable whether there is not more or less escape of gas around the bullet because of the expansion of the metal of the gun itself on the explosion of the charge. Since the introduction of nitro or so-called "smokeless" powders and hard-metal jacketed projectiles the evils attending this forward escape of gas beyond the projectile have been multiplied and no adequate means have thus far been devised to prevent it. With the old charcoal or black powder a very violent initial shock took place, and with the soft-lead bullet a more or less effectual sealing of the vent occurred at an early stage in the forward travel of the ball through the barrel of the gun. Nitro powder, on the other hand, appears much slower in its initial combustion, and when an attempt was recently made to use such powder in the Springfield rifle .45 caliber it was found

that the escape of gas was far greater than with the black powder theretofore used.

In modern high-power rifles of small caliber and quick twist a soft-metal bullet cannot be used, as the twist of the rifle at the high velocity imparted to the bullet strips the latter, causing it to jump the lands. Hence its flight is extremely erratic, and a bullet having a lead core and a hard-metal jacket or mantle is therefore employed. Such a bullet, however, owing to the presence of the mantle or jacket, offers great resistance to endwise compression, and consequently upsets with great difficulty. Hence it has been found necessary to make the bullet of a diameter equal to the measurement across the grooves of the rifling and to permit it to protrude from the mouth of the shell and to have as long and snug a bearing as possible in the entrance to the rifling. Unavoidable mechanical inaccuracies, however, prevent a perfect mechanical fit, and even if the latter were attainable it would only lessen and not prevent the escape of gas and consequent deformation of the bullet and injury to the rifling because of the before-mentioned expansion of the metal of the barrel itself under the high initial pressure of explosion. Moreover, a bullet of the character just mentioned, having but a shallow seating in the mouth of the cartridge-casing, is liable to work loose, and the casings are very often split at the mouth by the constant strain on the thin metal which has been forced over the end of the bullet with a "driving fit." To overcome these defects, resort has been had to various devices. For instance, a cup-shaped copper member has been attached to the base of the bullet; but this does not prevent the escape of gas, while it does give rise to another evil by frequently leaving the muzzle separated from the bullet, and therefore, of course, a source of danger to friendly troops in front and in the line of fire, or if separation does not take place the cup acts as a rudder and steers the bullet wildly. Another plan has been to simply recess the base of the bullet, so as to impart a flaring or cup shape thereto; but this does not set up quickly enough to prevent gas escape, and also detracts from accuracy of fire at high velocities.

I overcome the escape of gas around the pro-

jectile, whether in small-arms or large ordnance and whether a soft or hard metal projectile is employed, by utilizing the initial expansion of the cartridge-casing itself to seal

5 all forward vent, and do not depend upon any forward movement of the projectile to cause that end.

In the accompanying drawings, Figure 1 is a longitudinal section, on an exaggerated scale, of a small-arm cartridge embodying my invention. Fig. 2 shows the projectile for such cartridge as prepared for application to the cartridge-casing. Fig. 3 illustrates the application of the invention to a projectile 15 having a soft-metal point. Fig. 4 illustrates one method of adapting my invention to a soft-metal bullet. Fig. 5 shows part of a large-caliber projectile, illustrating the application of my invention thereto; and Figs. 6, 7, 8, and 20 9 are views illustrating other constructions embodying my invention.

Referring to Fig. 1, a cartridge-casing of the usual form is represented at 1 and the bullet at 2, said bullet having a jacket 3, which has 25 a cannelure or depressed portion 4, the metal of the jacket being formed at a point forwardly beyond this cannelure into a flange 5, which in the first instance projects outwardly from the jacket, as shown in Fig. 2. The 30 jacketed bullet is forced into the open mouth of the charged casing until the forward end of said casing contacts with the rear face of the flange 5, whereupon the forward portion of the casing is crimped into the cannelure 35 and the flange 5 is pressed down over said crimped end of the casing, as shown in Fig. 1. On the firing of the charge the first action which takes place is the diametrical expansion and longitudinal stretching of the casing 40 1, the gas-pressure tending to raise or force outward the depressed forward end of the casing, while at the same time the longitudinal stretching of the casing tends to force the bullet forward. Under the pressure thus 45 applied to the forward end of the casing the flange 5 of the jacket 3 is forced outwardly and against the wall of the cartridge-chamber, thereby effectually preventing any forward escape of gas, and as the pressure is 50 continued and the inertia of the bullet is overcome said flange 5 tightly hugs the wall of the cartridge-chamber, and when the rifling is reached said flange is forced downwardly and into the cannelure 4, so that when 55 the bullet issues from the muzzle of the gun no protruding part is presented to interfere with the true flight of the same.

When a soft-pointed bullet is used, the forward end of the partial jacket 6 can be bent 60 backwardly over the crimped forward end of the cartridge-casing, as shown at 7 in Fig. 3, so as to form the desired gas-checking flange. In this case the jacket for the reception of the bullet is in the form of a cup, which receives the base of said bullet and not only 65 forms the gas-check, but protects the base of

the bullet from deformation, such as would otherwise be caused by the upsetting action of the pressure upon it when the charge is fired.

70 In the case of an unjacketed bullet a flange 9 may be formed directly upon the bullet itself, as shown by dotted lines in Fig. 4, this flange being bent down over the crimped forward end of the cartridge-casing, as shown 75 by full lines in Fig. 4.

In large-caliber projectiles the flange may be formed upon the copper or other soft-metal driving-band 10 of the projectile, as shown, for instance, at 11 in Fig. 5, the driving-band 80 in this case having the cannelure 12, into which the forward end of the cartridge-casing is crimped or depressed.

The projectile shown in Fig. 6 has an oval or rounded base, which is a much better form 85 than a square base, so far as concerns the ease of flight of the projectile through the air. In this case the jacket 6, which envelops the rear end of the projectile and forms the gas-check 7, also serves to prevent deformation of the rear end of the projectile by pressure, and thereby insures the retention by the projectile of the desired rounded form of base originally imparted to it. When a projectile of this form is used without some 90 efficient gas-checking device, the forward passage of the gas surrounding the projectile seems to be assisted by the wedge-shaped space which surrounds the rear end of the projectile. Consequently the gas-checking 95 flange forward of the base is of peculiar advantage in connection with a projectile of this class. It is not essential to the proper carrying out of my invention, however, that the gas-checking flange should be located forwardly of the base of the projectile, as substantially the same operative effect in respect of gas escape can be secured by adopting the construction shown in Fig. 7, where the rear end of the jacket 3 constitutes the gas-check, 100 the rear end of the bullet being reduced in diameter, so as to afford an annular space inside the jacket, into which the forward end of the cartridge-casing can be entered.

In a cartridge of this character the reduced 105 portion of the base of the bullet may, if desired, be protected by a cap of hard metal, as shown, for instance, at 14 in Fig. 8, or, if desired, an annular groove may be formed in the soft metal of the bullet itself for the reception of the forward end of the cartridge-casing, as shown, for instance, in Fig. 9.

In addition to forming an efficient gas-check 115 the lip or flange on the projectile serves other useful purposes. For instance, it acts as a 120 positive stop to prevent the projectile from being forced back onto the explosive material in the cartridge-casing and is important in this connection, inasmuch as any encroachment upon the area of the explosive-chamber 125 serves to greatly raise the breech-pressures when the charge is fired. Furthermore, the 130

presence of the overlapping flange insures a much firmer seating of the projectile in the mouth of the cartridge-casing than when the projectile is simply driven into said mouth, 5 as usual, the projectile having a frictional hold upon both the inside and outside of the cartridge-casing instead of upon one side only. Consequently the casing will not split at the mouth and a comparatively short bite 10 suffices to retain the projectile in place, this being of especial advantage in multishot cartridges, such as those shown and described in my application, Serial No. 40,675, dated December 21, 1900, in which the grip of the 15 casing upon the base of the leading bullet is necessarily very short. In such a cartridge a gas-checking device is of prime importance in connection with the leading projectile, but is not desired in connection with the following one, escape of gas around the latter being one of the means depended upon to ignite the charge which is interposed between the two projectiles.

I am aware that it has been proposed to secure a bullet to the forward end of a cartridge shell or casing by means of a flange overlapping said forward end and pressed down firmly into contact with the casing; but in all prior cartridges of this class with which I am 25 familiar the casing was intended to be discharged from the gun with the bullet. Hence the flange upon the latter did not serve as a gas-check, for in order to perform this function the projectile must when the gun is fired 30 be separated from the cartridge-casing, the latter remaining in the breech of the gun.

Having thus described my invention, I claim and desire to secure by Letters Patent—

40 1. A projectile having a flange thereupon so disposed as to overlap the mouth of the casing which receives the explosive charge, whereby, when the projectile is fired, said flange will be expanded so as to serve as a 45 gas-check.

2. A cartridge having a casing constructed for retention in the gun, and a projectile with gas-checking flange overlapping the mouth of said casing.

50 3. A projectile having a gas-checking flange and a cannelure into which said flange can be forced as the projectile passes through the bore of the gun.

4. A cartridge having a casing constructed 55 for retention within the gun, and a projectile having a gas-checking flange and a cannelure adjacent thereto into which the forward end of the casing is crimped, said forward end of the casing being overlapped by the gas-checking flange.

5. A cartridge having a casing constructed for retention in the gun, and a projectile with gas-checking flange overlapping the mouth of said casing, whereby the latter has both internal and external frictional contact with the projectile.

6. A projectile having a jacket with gas-

70 checking flange formed from the metal of said jacket, and constructed to overlap a casing which receives the rear end of the projectile.

7. A cartridge comprising a projectile with jacket having a gas-checking flange formed thereon, and a casing whose mouth is overlapped by said flange.

75 8. A projectile having a jacket which incloses only a portion of the projectile and has an external flange which constitutes a gas-check, and is constructed to overlap the mouth of the cartridge-casing which receives the rear end of the projectile.

80 9. A cartridge having a casing for receiving the explosive charge, and a projectile provided with a jacket which incloses only a portion of the projectile and has a flange overlapping the forward portion of the casing 85 and serving as a gas-check.

10. A projectile having its base portion contained within a jacket whose forward portion forms a gas-checking flange.

90 11. A cartridge having a casing for receiving the explosive charge and a projectile having its base portion contained within a jacket whose forward portion forms a gas-checking flange overlapping the forward portion of the cartridge-casing.

95 12. A cartridge comprising a casing for receiving the explosive charge and a projectile having a cannelure formed therein and having its base portion contained within a jacket whose forward portion forms a gas-checking flange which overlaps the forward portion of the casing and is pressed into said cannelure.

100 13. A jacket constructed to envelop a portion of a projectile, said jacket having thereon a flange so located as to receive within it 105 the forward portion of a cartridge-casing in connection with which the projectile is intended to be used.

110 14. A jacket constructed to envelop a portion of a projectile and having at its forward end a flange so located as to receive within it the forward portion of a cartridge-casing in connection with which the projectile is intended to be used.

115 15. A projectile having a rounded base, and a gas-checking flange in advance of the same.

120 16. A projectile having a rounded base and a jacket inclosing the same so as to prevent its deformation by the upsetting pressure of the gases of explosion.

17. A projectile having a rounded base, a jacket for inclosing the same, and a gas-checking flange in advance of the base.

125 18. A projectile having a rounded base, a jacket for inclosing the same, and a gas-checking flange formed from the metal of said jacket.

130 19. A cartridge having a charge-containing casing and a projectile with rounded base, and a gas-checking flange in advance of said base, and overlapping the mouth of the cartridge-casing.

20. A cartridge having a charge-containing casing, and a projectile having a rounded

base, and a jacket forming a flange which overlaps the mouth of the casing.

21. A cartridge having a charge-containing casing and a projectile having a rounded base, 5 and a jacket inclosing said base and forming a flange which overlaps the mouth of the casing.

In testimony whereof I have signed my name to this specification in the presence of two subscribing witnesses.

ROBERT W. SCOTT.
